UNITED STATES PATENT OFFICE.

WARREN H. TAYLOR, OF STAMFORD, CONNECTICUT, ASSIGNOR TO THE YALE
& TOWNE MANUFACTURING COMPANY, OF SAME PLACE.

LOCK.

SPECIFICATION forming part of Letters Patent No. 412,997, dated October 15, 1889.

Application filed February 12, 1889. Serial No. 299,600. (Model.

To all whom it may concern:

Be it known that I, WARREN H. TAYLOR, of Stamford, in the county of Fairfield and State of Connecticut, have invented certain new and useful Improvements in Locks, of which the following is a specification, reference being had to the accompanying drawings.

The object of my invention is to provide an improved lock of simple construction that can be operated by either of two different keys which cannot be interchanged.

My invention is especially applicable in practice to such uses as require that each one of a series of locks shall be capable of being operated by a change-key which will open it and no other, and that a master-key be provided which will open the whole series. Such a lock, for instance, would be especially useful in hotels and buildings with a large number of office-rooms.

A lock which shall perfectly fulfill the above conditions has long been sought for; but in almost all cases failure in considerable measure has resulted, chiefly because the setting of the locks to a master-key has impaired their security and lessened the number of change-keys which can be fitted to them. Heretofore the tumblers on which the change-key acts have not generally been independent of the tumblers on which the master-key acts. It has been attempted to have the master-key and the change-key act on different parts of the same tumblers; but this has rendered the locks too costly and has not given entire satisfaction.

In nearly all locks which have had the tumbler-and-bolt-actuating mechanism in the same case the tumbler-fence has been attached to the bolt and moved forward and backward with it. It is not possible with that construction to make a set of tumblers that will bear the same relation to the fence whether the lock is locked or unlocked, which, to accomplish my purpose, is a necessary condition.

In my lock the tumblers and bolt-actuating mechanism are in the same case, and the bolt is actuated by either of two keys, each of which is provided with its own independent set of

tumblers. I have provided a novel combination of tumblers and fence-levers, and have removed the tumbler-fence from the bolt and placed it at the ends of the tumblers on a dogging-lever, which is actuated by the movement of the bolt, and returns to the same position after the bolt has been moved fully in either direction.

In a broad sense, the general plan of operation of my lock has been already shown in the lock patented by Henry R. Towne, No. 206,646, dated July 30, 1878; but that lock is one in which the tumbler mechanism is contained in a separate escutcheon or tumbler-case, although the tumblers and cam or wing for throwing the bolt return to the same position after the bolt has been thrown forward or retracted.

In the accompanying drawings, Figure 1 is a plan view, partly in section, of my improved lock with the cap removed, showing the relation and arrangement of the parts in the locked position. Fig. 2 is a similar view to that shown in Fig. 1, with the lower half broken away and the bolt partially retracted. Fig. 3 is a section on the line 3 3 of Fig. 1. Fig. 4 is a detached view of the bolt provided with my pivoted stump, showing in dotted lines the relation of the parts when the bolt is retracted. Fig. 5 is a view similar to that shown in Fig. 4, showing the bolt partially cast. Fig. 6 illustrates a group of detached parts of my lock in perspective. Fig. 7 illustrates one key, and Fig. 8 the other.

Referring to the letters on the drawings, A represents an ordinary lock-case provided at the lower part with the ordinary latch mechanism, which is too well known to require description, and which forms no part of my invention.

In the upper part of the case is illustrated what constitutes my invention, where B is a bolt provided with the arms C C', against which the keys act. The bolt carries a stump D, pivoted to it at D'.

E E' indicate dogs in the form of bell-crank dogging-levers, provided at one end with the fences F F' and pivoted upon the pin G. At their opposite ends, where these levers come

together, is formed a recess G', to receive the projection D² of the stump when the bolt is retracted.

5 H H' indicate two separate sets of tumblers pivoted upon the pins X X', respectively, and provided with springs I I' and gatings J J'.

Y Y' indicate projections upon the ends of the tumblers, which bear upon the fences F F', respectively, when the tumblers are released 10 from the actuation of the key.

15 The springs I bear against the upper part of the case, and the springs I' against a bearing K on the dogging-lever E. By this means the springs I' also serve to support the dogging-lever E.

20 L is a spring pivoted upon the pin M, and bearing at one end upon the case A and at the other upon the bearing K' upon the dogging-lever E'.

25 N is a key-hole adapted to receive the key O, which I will call the "master-key," although either key may be made to perform the office of a master-key.

N' is another key-hole adapted to receive 25 the change-key O'.

P is a guide-slot in the arm C', adapted to receive the guide-pin Q, which is secured to the case A and limits the forward and backward movement of the bolt.

30 To illustrate the operation of my lock, let it be assumed that the bolt is cast and the key O inserted in the upper key-hole. Upon turning it in the usual manner the wing of the key engages with the tumblers H and elevates them until their gatings are opposite the fence F upon the dogging-lever. Then the key-wing strikes the arm C of the bolt, moves it back, and forces the projection D² of the stump D against the ends of the dogging-levers 40 with a wedge action tending to separate them. This causes the dogging-lever E to turn on its pivot and the fence F to enter the gatings J. The projection D², after passing between the ends of the dogging-levers, enters 45 the recess G' provided for it. The key then having completed its rotation and passed out of engagement with the arm C, the springs I' force the end of the dogging-lever E upward and retract the fence F from the gatings, allowing 50 the tumblers, by force of their springs, to assume the same position that they occupied in the first place. In the same manner the key O' may be used to operate the bolt through its insertion and rotation in the lower key-hole; but the spring L in this instance restores 55 the dogging-lever E' to its original position.

In Figs. 2 and 5 it is shown how the pivoted stump turns to one side or the other in 60 order to pass one dog, which remains rigid while the other dog is turned on its pivot by the force of the key acting on the bolt and projection D² of the stump. It will now be evident that the bolt can be cast or retracted 65 by either key independently of the other, and that the action of one key and the locking

mechanism operated by it does not affect the other set of locking mechanism, the double inclines of the sides of the projection D² acting on the double inclines of the ends of the 70 dogging-levers by the use of each key to turn one lever on its pivot, as above described.

In the accompanying drawings the dogging-levers are shown as bell-crank levers; but this form is not material, the essential 75 thing being to interpose some piece between the bolt and the tumblers which shall be dogged by the tumblers when not set by the key, and which, until the tumblers are so set, will form an obstruction to the passage 80 of the bolt.

The construction shown in the drawings illustrates one way that I prefer of accomplishing my purpose, which is to secure the lock against being locked or unlocked with-out the use of one of its proper keys. Two ends of the dogging-levers rest together against a projection from the stump of the bolt, and until the tumblers are thrown into the proper position the bolt cannot be cast or 90 retracted; but when either group of tumblers is set by the proper key the continued rotation of the key will move the bolt backward or forward, and as it moves the movable stump will push aside the dog whose tumblers are 95 set, the stump itself moving around the dog whose tumblers are not set. When the bolt has been fully cast or retracted, the dogging-lever and tumblers will assume their former position, so that the bolt can be operated by 100 either key. It will thus be seen that I have produced a master-key lock in which one tumbler mechanism is absolutely independent of the other, so that the capacity for permutations either on the change-key or the master-key is unimpaired, and the security against picking either through the change-key mechanism or the master-key mechanism is not in 105 the least diminished.

In addition, my lock has an advantage in 110 manufacture, because in fitting keys and adjusting tumblers of one set of locking mechanism no attention need be paid to the adjustment of the tumblers of the other set of locking mechanism.

115 I have referred throughout to tumblers as being the means of security used in this lock. I have done this because the use of tumblers is the most approved method of getting security; but it is evident that with one tumbler for each key, or without the use of any tumblers, the dogging mechanism would work, and made in duplicate would still serve the purpose of this invention if, in place of tumblers, wards or other obstructions were used 125 to afford more or less security against picking, wards or obstructions being well-known equivalents in the art of lock-making for tumblers.

130 Instead of having two keys, it would of course be practicable to make the tumbler mechanisms both alike and operate the lock

wholly by a single key; but that will not generally be desirable.

What I claim is—

1. In a key-lock, the combination, with the bolt and two independent sets of tumblers, of two movable dogs and a fence upon each dog adapted to enter the gatings of the tumblers when set in alignment, and a separate key to operate each set of tumblers and the bolt, substantially as set forth.
2. In a lock, the combination of a bolt, a movable stump, and two movable dogs, substantially as set forth.
3. In a lock, the combination of a bolt provided with key-arms C C', two independent tumbler mechanisms, two independent keys, a movable stump upon the bolt, and movable

dogs engaging with the stump at one end and with tumbler mechanism at the other end, so as to hold the bolt either in the locked or 20 unlocked position, the whole so arranged that each key will operate one set of tumbler mechanism, one of the movable dogs, and the bolt, substantially as set forth.

4. In a lock, the combination of a bolt carrying a movable stump, with a movable dog carrying a fence, and a tumbler mechanism, substantially as set forth.

In testimony of all which I have hereunto subscribed my name.

WARREN H. TAYLOR.
